UNITED STATES PATENT OFFICE

PAUL DANCKWAERT, OF DENVER, COLORADO.

APPARATUS FOR MAKING GASOLINE FROM CRUDE OIL

1,817,077.

Specification of Letters Patent. Patented Sept. 22, 1912.

Application filed August 27, 1911. Serial No. 188,306.

To all whom it may concern:

Be it known that I, PAUL DANCKWAERT, a citizen of the United States, and a resident of Denver, in the county of Denver and State of Colorado, have invented new and useful Improvements in Apparatus for Making Gasolene from Crude Oil, of which the following is a specification.

This invention relates to an apparatus designed particularly for carrying out my improved process for the production of gasoline from crude oil, as described in detail and claimed in an application for Letters Patent I am filing simultaneously herewith.

The example of my apparatus shown in the accompanying drawings will now be described in detail, and the distinctive novel features will then be pointed out in the appended claims.

In said drawings, Figure 1 is an elevation of such apparatus, with parts in section;

Fig. 2, an elevation with parts in section on line 2—2 Fig. 1;

Fig. 3, is a horizontal section on line 3—3 Fig. 2;

Fig. 4, is a vertical section on line 4—4 Fig. 1. In all the figures, the same numerals designate the same parts.

In Fig. 1 numeral 1 represents the still proper, while 2 is an elevator connected with the still at the bottom and top through the large lower pipe, or compartment 3 and the upper discharge pipe 4. The elevator 2, made of steel chain and perforated steel buckets, is inclosed in a steel pipe 5. The sprocket wheels 6 and 7 of the elevator are set on horizontal shafts leading through the wall of the upright pipe 5 and the lower horizontal pipe 3. The elevator is driven best by a pulley on the top shaft, as shown in Fig. 4. The still 1 consists of an iron cylinder 8 closed by bottom plate 11 and top plate 12, and has an inside lining 9 of a suitable refractory material. The inside space slants toward the compartment 3. Through the walls of the still horizontal carbon electrodes 13 protrude, superposed on each side of the still and reaching outside into iron pipes 14, as shown in Fig. 2. More electrodes than are shown in the drawings may be used, one above the other to heat a larger area of the still. Into the carbon electrodes are screwed copper rods 15, provided with handles 16. Insulating ma-

terial 17 is placed between flanges and rings 18 held together by bolts. Preferably a refractory arch or brick 19 is placed above the electrodes as shown, to protect them from the weight and impact of the descending material, it being understood that such material may pass down through openings left at each side of the said brick 19. A light gas pressure is produced during the operation, and for this reason and to prevent the escape of gas between the insulating material 17 and the copper rods 15, I place a packing 17' of asbestos or other suitable material between the beveled inner edges of the insulating rings 17, around the rods 15; this packing is compressed by the flanges and rings to form a tight joint around the rods. By means of cross bars and clamps 18 and 19 connection is made with the poles of a dynamo. 20 and 21 are pipe connections, 20 for the introduction of air and 21 is the inlet for the charge. The lower compartment 3 is provided with an outlet pipe 22 leading by way of the pump 23 to the scrubber or container 24, which holds the bulk of the oil to be treated. The bottom of this high cylindrical container is connected by means of a pipe 25 and pump 26 with the upper part of the container, and through a branch pipe 27 with the interior of 3. Valves 28 and 29 allow the direction of the flow of the fluid to be controlled. Inside of compartment 3 a metal screen 28 is clamped to a circular angle ring 29. The vapor pipe line 30 discharges near the bottom of container 24. The latter, closed on top and bottom has the outlet pipe 31 for vapors and fixed gases and the inlet pipe 32 for fresh oil.

I desire it to be understood that the apparatus may be modified in various ways without departing from the nature of my invention as specified in the appended claims. More particularly, the electrodes and their connections may be omitted, as in some cases the necessary heat can be produced in other ways as indicated below, but in most cases, I consider the apparatus with electrodes preferable. If the electrodes are omitted, it is desirable to make the still proper considerably higher than when using the electrodes.

One way of using the apparatus shown in the drawing may be described as follows:

I introduce into the apparatus at the pipe

connection 21; a charge consisting of a material rich in aluminium oxid (bauxite, etc.) and carbon (coke graphite etc.) metal chlorid, one or more metals or metal oxids (iron, nickel, zinc, lead; antimony, titanium, calcium, magnesium or other suitable ones) the chlorids of which are easily decomposed by heat in the presence of hydrogen or steam. The charge ought to contain a high percentage of carbon so as to prevent it from caking at the temperature of the furnace. As an example, the following proportions may be employed: 85% of carbon, 5-10% of metal chlorid, and 5-10% of metal or metal oxid. I then ignite some wood and charcoal on top of the charge and having started the blower connected with the pipe 20, let the blast play on the burning charge. When it is well ablaze, I close valve 21 and begin the operation of the elevator. This fills pipe 4 with the charge. The valve 21 being closed, the blast is mostly forced downward through the charge and if container 24 has been about half filled with oil previously, the hot gases are forced through the oil by way of the pipe 30. As 80-85% of the charge consists of coke, the gases will not contain any dangerous amount of oxygen, as they have to pass through a long column of glowing coke which exerts its reducing effect on them. In a short time, the charge in 1 is brought to redness and the oil in 24 commences to boil. When this point has been reached, I lower the blast or cut it out altogether and start the dynamo all connections having been made beforehand. The temperature soon rises to such a degree, that decomposition of the chlorids will begin, iron chlorid for instance breaking up into chlorin and iron and with any moisture present, forms hydrochloric acid and iron. At the same time, the current reduces some of the aluminium oxid. The liberated aluminium may or may not become alloyed with the iron or any other metal present. This depends on the amount of current and heat employed. I aim at just reducing part of the aluminium oxid and regulating the current and distance of the electrodes and the speed of the elevator accordingly. While the elevator is continually withdrawing charge from the bottom and dumping it into the top of the furnace or still, I start pump 26 and set valves 34 and 33 so that a good stream of oil is directed through 27 upon the hot descending charge at the bottom of 1. Soon the charge now containing principally reduced metal and carbon with the chlorids and hydrochloric acid intermingled with it, reaches the level of the foot of the elevator where it meets the stream of oil. Under the cooling effect of the oil, the hydrochloric acid gas recombines with the metals, reforming chlorids of the metals. Chlorid of aluminium, however, is formed

already from its oxid and hydrochloric acid in the presence of carbon at a level above the outlet. At the same time, the hydrogen set free exerts its affinity *in statu nascendi* upon the oil, and the chlorids, particularly the aluminium chlorids exert their influence as catalysts. Both reactions assist each other, and while the reaction is not yet completed in 3, a large part of the crude oil is here already changed into compounds of relatively low boiling points. In the meanwhile, pump 23 has been started also. Thereby any oil and the finer part of the charge which is able to escape through the screen 28 are conveyed to the container 24. Here the ascending current of vapor and gases meets the descending mixture of oil and fine charge. At the temperature existing there, very favorable for the formation of chlorids, the remaining free hydrochloric acid combines with the metals forming more chlorids and completes the process of addition of hydrogen. These chlorids, together with carbon and fine oxid of aluminium and oil are continually sucked off through pump 26 and partially discharged into 3 through pipe 27, partly through pipe 25 back into container 24. At the same time the elevator carries all the coarser charge together with some fine charge and as much oil as may adhere to the charge into the top of the still 1. Here it descends gradually and as it meets an increasing temperature the oil gradually distils off, escaping through pipe 4 and the elevator into compartment 3, where it mingles with the rest of the vapor formed at the point of junction of the descending charge and the oil injected through pipe 27. I aim to regulate the resistance to the passage of the vapor so that only a small part of any oil vapor formed above the hot zone is forced through it, because the high temperature between the electric poles would destroy a large part of it and break it up into carbon and hydrogen. The charge, in descending, therefore, ought to reach the hot zone where the chlorids, formed in the cooler parts of the apparatus, are again decomposed, "dry" that is in a state free of oil. From this point on, the reactions follow again then in the same order as stated above.

Hence we can perceive that continually fresh aluminium chlorid is formed beginning at the hottest point of the still, while the other chlorids are formed only in those parts of the apparatus where oil is present in sufficient quantity to cool the charge down to the required point. For there is this great difference with regard to the formation of the different chlorids. Aluminium forms its chlorid best at a high temperature, and it is not necessary at all first, to reduce the oxid to the metallic state by means of the current. If the temperature

and the atmosphere are favorable aluminium chlorid will form at the poles according to the formula

When all the oxid which was introduced with the charge at the beginning of the process, has been changed into chlorid, any further chlorid is formed from the spent chlorid, which is brought up through the elevator continually. Such spent chlorid has become hydrated, that is, it has taken up oxygen and hydrogen from any water contained in the oil. This hydrated chlorid in descending toward the hot poles breaks up into aluminium oxid and hydrochloric acid and oxygen which latter combines with carbon to form CO. The aluminium oxid thus formed instantly under the influence of the electric current is partly reduced to metal, partly forms directly aluminium chlorid with the hydrochloric acid present. Any part of the aluminium reduced to the metallic state may by alloying with other metals present, escape with them downward to the zone where the oil enters and where all the metals are disintegrated to again form chlorids.

As to the amount of air that may be allowed to be blown into the still to promote combustion and thus assist the current in heating the charge, I will say that it seems to interfere to some degree in so far as it oxidizes the carbon poles if too great a quantity of air is employed. If, however, the apparatus is high enough for a perfect reduction, it only interferes with the ultimate condensation of the gasoline.

The container 24 I prefer to build high and I fill it only about half with oil, or two containers in series may be used. In this way, I can regulate the process so that the temperature at the outlet 31 does not rise much above 150° C. The product leaving 31 under these conditions is a well saturated oil of low gravity and a clean smell and clear as water. It can be marketed as a first class gasoline.

After a while, the oil in container 24 becomes thicker and heavier, though it was supposed that new oil is continually or intermittently added at the top. If it is desirable to work this oil containing heavy parafin oils, into lubricating oil, it may be withdrawn and treated for that purpose by any existing method. The process, therefore, offers a means to produce gasoline directly from crude oil and can be used either to turn out only gasoline, or the process may be interrupted and the remaining oil worked into more remunerative products according to the market demands.

While the process is going on, naturally some fixed gas and carbon are formed, though in this respect, this process is su-

perior to so called "cracking" processes employing higher temperatures and pressures. Nevertheless, the carbon thus accumulating and continually transported into the still, would at last choke the apparatus, if it was not consumed in some way or another. This is partly done by the chemical reactions of the process, particularly that between oxids and carbon and between steam and carbon. Should carbon nevertheless, accumulate, a blast will consume the excess easily.

From the above description, it is obvious that this process can be conducted in a variety of ways, without affecting the underlying principle. First we may use the blast only for starting to heat up the whole apparatus, then continue with electric heating alone. Or it may be continued more or less, or intermittently, while the current is used simultaneously. Often without the current the process will work, on blast alone, but the vapors are then mixed with a large amount of fixed gas and more difficult to condense. In such a case, also, the presence of steam demands that the furnace must be constructed considerably higher in order to insure a perfect reduction to H₂ and CO.

I claim:

1. An apparatus of the class described, comprising a still provided with electrodes, an elevator located exteriorly of the still, for transferring material from the lower portion of the still to the upper portion thereof, a container located exteriorly of the still, a connection for supplying material from the container to the lower portion of the still, and a connection for conveying products from the lower portion of the still to the lower portion of the container.

2. An apparatus of the class described, comprising a still provided with electrodes, an elevator for transferring material from the lower portion of the still to the upper portion thereof, a container located exteriorly of the still, a connection for conveying material from said container to the lower portion of the still and another connection for conveying material from the lower portion of the still to the container.

3. An apparatus of the class described, comprising a still provided with electrodes, an elevator for transferring material from the lower portion of the still to the upper portion thereof, a container located exteriorly of the still, a double connection connected with the still between the elevator and the upper end of the still, and with the container at the bottom and at the upper portion thereof, a second connection extending from the upper portion of the container to the lower portion of the still, and a third connection extending from the lower portion of the still to the lower portion of the container.

4. An apparatus of the class described,

comprising a still provided with electrodes, means for transferring material from the lower portion of the still to the upper portion thereof, a container located exteriorly of the still, connections extending from the lower end of the still to the lower portion and the upper portion respectively of the container, a screen located in the still between said connections and the transferring 10 means, and an additional connection leading

from the container to the still at a point between its upper portion and the lower end of the transferring means.

5. An apparatus of the class described comprising an upright still, superposed 15 horizontal electrodes projecting into said still, and a container connected with said still.

PAUL DANCKWARDT.
